UNITED STATES PATENT OFFICE.

BENJAMIN F. MAYO, OF SALEM, MASSACHUSETTS, ASSIGNOR TO UNITED SHOE MACHINERY COMPANY, OF PATERSON, NEW JERSEY, A CORPORATION OF NEW JERSEY.

SOLE-PRESSING MACHINE.

1,146,341.

Specification of Letters Patent. Patented July 13, 1915.

Application filed May 28, 1910. Serial No. 563,838.

To all whom it may concern:

Be it known that I, BENJAMIN F. MAYO, a citizen of the United States, residing at Salem, in the county of Essex and State of Massachusetts, have invented certain new and useful Improvements in Sole-Pressing Machines; and I do hereby declare the following to be a full, clear, and exact description of the invention, such as will enable 10 others skilled in the art to which it appertains to make and use the same.

The present invention relates to sole pressing machines which are employed to lay and level the soles of boots and shoes 15 during the process of manufacture. Heretofore, these operations have generally been performed by machines of two classes or types, commonly called "direct pressure" and "rolling pressure" machines, respectively. In the former class of machines a sole pressing mold or form is employed which is applied under pressure to the entire surface of the sole simultaneously by a relative movement of shoe supporting jack 20 and sole pressing form directly toward each other in a straight line, the form being suitably shaped to press or mold all portions of the sole at the same time into the desired shape or contour. While this type 25 of machine tends to mold the sole invariably into the same shape or contour, on account of the simultaneous engagement of its form with all portions of the sole, difficulty is often experienced in properly laying or leveling certain portions of the sole, particularly the shank portion, on account of the comparatively light pressure per unit area under which the machine is obliged to operate, for otherwise the wooden lasts which 30 are commonly employed to support the shoes when they are subjected to the action of this machine would be broken or damaged by the heavy total pressure exerted upon the sole as a whole by the simultaneous 35 application of pressure to all of its parts. In the rolling pressure machines, on the other hand, a sole pressing form or roll is employed which is applied temporarily first to one portion of the sole and then to 40 another by a relative oscillating or rolling movement of form or roll and jack. These machines, however, although capable of operation under a much higher pressure per unit area than direct pressure machines 45 without endangering the lasts, apply their

pressure along what is practically only a line contact between the form or roll and sole and extending across or only partially across the latter. As a consequence, machines of this type tend to produce soles of 50 different and varying shapes and contours. Moreover, the progressive relative movement of the form or roll along the sole while in contact therewith tends to displace and distort the sole. 55

One of the objects of the present invention is to devise a sole pressing machine employing a sole pressing form which shall subject the shoe sole to a sufficiently heavy pressure per unit area to mold the sole to 60 the exact shape or contour desired, yet without causing so heavy a total pressure to be imparted to the last that it is liable to be broken or otherwise damaged. This result is obtained by mechanism so constructed and 65 operating that a heavy pressure will be applied successively to substantial portions of the surface of the sole, such pressure being subsequently relieved in whole or only in part so that at no time is the total pressure 70 upon the last sufficiently high to fracture or to otherwise damage it. 80

Another objection not only to direct pressure machines but also to those rolling pressure machines employing a form is that no 85 means are provided to enable these machines to apply pressure to one portion of the shoe sole, such as the shank portion, either heavier per unit area or for a greater number of times or for a longer duration of 90 time, than to other portions such as the ball and toe, but in order that these prior machines may properly lay or level the most difficult portion of the sole all the remaining portions must be subjected to a heavier 95 pressure or to a greater number of pressures or for a longer period than are necessary or desirable.

One of the objects of the present invention is to devise a sole pressing machine employing a sole pressing form which shall avoid this defect and which may operate to impart to certain portions of the shoe, and preferably to the shank, a heavier pressure or a greater number of pressures or pressure for a longer period than are applied to other portions of the sole, particularly the ball and toe portions. 105

Other novel features of the present invention reside in the form, the form carrier, 110

the shoe supporting jack, and in other devices and mechanisms as will be apparent to those skilled in the art.

In the accompanying drawings which illustrate what is considered the preferred embodiment of the present invention that has as yet been devised, an automatic twin or double machine is illustrated, driven from a common source of power and constructed and arranged as is common in the boot and shoe machinery art to allow one set of mechanisms to operate while the other set is in inoperative position to permit the introduction or removal of the work or the making of necessary adjustments.

In these drawings, Figure 1 is a side, and Fig. 2 a front, elevation of such a machine; Figs. 3 and 4 are vertical sectional views of the shoe supporting jack and of the sole pressing form, the latter being shown in Fig. 3 in inoperative position and out of contact with the shoe sole, and in Fig. 4 in inoperative position and in contact with the sole; Fig. 5 is an enlarged vertical section of the sole pressing form and the carrier for the same; Fig. 6 is a front elevation of a portion of the form and carrier; and Fig. 7 is a transverse sectional view of the same on line 7-7, Fig. 5; Fig. 8 is a top plan view on line 8-8, Fig. 4, partially in section, of the shoe supporting jack and its adjusting mechanism; and Fig. 9 is a transverse sectional view of the same on line 9-9, Fig. 4.

Since the two sets of jack and form mechanisms, as well as their actuating devices, are identical, only a single set will be described in detail.

In the specific form of the invention, which is illustrated in the drawings, the shoe is supported upon a jack normally held in fixed position and a flexible sole holding form comprising a plurality of sections hinged or pivoted to one another is applied to the sole, one portion or section at a time, by a spring-pressed roll or carrier over which the form is wrapped or wound, the rolling of the carrier along the shoe unwrapping the form and laying it upon the shoe sole. The carrier when rolled in the reverse direction wraps or winds up the form, carrying it out of engagement with the sole of the shoe. A plurality of spring-pressed rolls are provided which follow directly behind the carrier in its form-applying movement, which rolls engage the back or upper surfaces of the sections of the form and apply and maintain pressure on the form.

As shown in Figs. 1, 3 and 4, the last 1 which carries the shoe, the sole of which is to be laid or leveled, is supported in the usual manner at the heel and toe by the heel and toe supports 2 and 3, respectively, of 65 the jack carried on the frame of the ma-

chine. Pivoted upon the horizontal shaft 5, which is fixedly secured in suitable supports or bearings at the front of the machine, are the sector levers 6, projecting from the hubs 7 of which are the actuating arms 8. The 70 sector levers 6 are provided at their extremities with the arc-shaped portions 9 in which are formed a plurality of parallel sided radial slots 10, the front end of the arc-shaped portions being formed with a 75 projection 11 having the parallel-sided, radial slot 12. Mounted in the slot 12 in each sector lever 6 is the bearing block 14 in which the shaft 15 is rotatably mounted. Rigidly mounted upon this shaft is the 80 form carrier which comprises the hub 16 and a semi-cylindrical body portion 17, integrally connected with the hub by means of the radial arms 18. The outer face of the semi-cylindrical portion 17 is formed with 85 a plurality of slightly concaved, arc-shaped faces, the elements of which are parallel to the axis of the shaft 15.

The sole pressing form shown in enlarged detail in Figs. 5, 6 and 7 is a flexible form 90 and comprises a plurality of sections or links 21 pivoted to one another and each carrying a sole engaging piece 22 composed of some suitable slightly yielding material such as rubber, and having its outer surface of the proper and desired contour for that portion of the shoe sole with which it is to be brought into contact. The method of connecting the sections or lugs 21 is perhaps best illustrated in Fig. 6, where each link 95 is shown as being provided with two lugs or projections 23 on what would be the rear edge of the link when the form is in contact with the shoe sole, which lugs come just within the lugs 24 on the front edge of the 100 adjacent link, a pivot pin 25 passing through the two lugs 23 and 24 and securing the sections or links together. Each link or section is also provided with a recess 26 in its rear edge and a correspondingly shaped projection 27 at its front edge, the projections on one link entering the recesses in the adjacent link, thus breaking the line of jointure on the adjacent links and insuring a continuous surface for the engagement of the supplementary pressure rolls which will shortly be described. The means for securing the yielding sole engaging members 22 to the links 21 comprise 115 screws 28 passing through the projections 120 or bosses 29 on the links and entering the members 22.

While the sole pressing form, as illustrated in the drawings and as above described, constitutes a combined flexible and sectional form, the present invention, except where so specifically defined, is not limited to such a construction as it is evident that with either a flexible or a sectional form not only may pressure be applied progressively 130

and successively to one portion of the sole after another, but different pressures both as to amount and as to duration may be imparted to different portions of the sole.

5 The heel end of the form is anchored to the post 31 which is mounted in the block 32 secured upon the jack support, the post being arranged for a vertically yielding movement against the coiled spring 33. The 10 toe end of the form is pivotally connected to the lugs or bosses 34 on the carrier. Except for these attachments of the rear end of the rear section to the post 31 and the front end of the front section to the lug 34, the 15 form is free and unsecured, the intermediate portions being supported upon the faces 19 of the carrier when in inoperative position, as shown in Figs. 3 and 5, or resting in engagement with the shoe sole, as shown 20 in Fig. 4, when in operative position.

It is obvious that if the sector lever be actuated by suitable mechanism to move it to the left as shown in Fig. 3, the form carrier will be oscillated anti-clockwise by the 25 form itself, the rear end of which is anchored as described, and the form will be laid, one portion after another, upon the bottom of the shoe sole until the parts have been brought into the position shown in Fig.

30 4. In order that a reverse movement of the sector lever shall cause the carrier to oscillate in the opposite direction and to wrap or wind up on itself, as it were, first one portion and then another of the form, mechanism has been provided which operates independently of the form to accomplish this 35 result. This mechanism comprises a grooved wheel or pulley 37, rigidly secured to the shaft 15 upon which the carrier is fixedly 40 mounted, a fixed segment 38 mounted upon the frame of the machine and having a groove in its peripheral face, and a wire 39, or other flexible connection, one end of which is secured at 41 in the front end of 45 the groove of the fixed segment while the other end is secured at 42 in the grooved wheel 37. The lead of the wire is best shown in Fig. 3, extending in the groove in the fixed segment from its point of attachment 50 at 41 nearly to the rear end of such segment and thence passing around the back of the pulley 37 and in its groove to the point of attachment at 42. When the sector lever is moved to the left, as shown in Fig. 3, the 55 oscillation of the form carrier causes the wire to be wound around the grooved pulley 37, the wire finally assuming the position shown in Fig. 1 on the left-hand grooved pulley. On the reverse or rearward 60 movement of the sector lever, the wire being anchored at 41 acts just as did the form in the forward movement and compels the carrier to oscillate in a clockwise direction and to wind up upon itself the form.

65 It will be noted that the above described

mechanism positively oscillates the carrier in its form removing movement and insures the proper positioning of the form upon the carrier and its subsequent application to the sole of the next shoe.

The pressure applying devices which act to force the form strongly against the shoe sole to lay or level the same, include not only the form carrier itself which preferably exerts a heavy pressure upon each portion of the form as it is brought into contact with a portion of the shoe sole, but also a series of supplementary pressure applying devices in the shape of spring-pressed rolls carried by the sector lever and caused to roll 70 over a greater or less number of sections of the form after it has been brought into contact with the shoe sole. The form carrier acts as a pressure applying device through the medium of the relatively heavy coiled 75 springs 45 located in the top portion of the radial slots 12 in which are mounted the bearing blocks 14, which in turn support the shaft 15 carrying the form carrier. The lower end of the springs 45 engages the top 80 of the bearing blocks 14 while the upper end of each spring bears against a washer or pressure plate 46 adapted to be adjusted up and down in the slot by means of the adjusting screw 47 to adjust the pressure exerted 85 upon each section of the form as it is brought on to the shoe sole.

The supplementary pressure rolls 51, of which four are shown in the machine illustrated in the drawings, are rotatably mounted 90 in bearing blocks 52 located one in each of the radial slots 10 in the sector levers 6, the blocks being normally pressed inward toward the axis of the levers by the relatively light coiled springs 53, one end of 95 100 which engages directly with the bearing block while the other bears against a washer or pressure plate 54 arranged to be adjusted through the medium of the adjusting screws 55 to vary the pressure exerted by the rolls 105 51. If desired, these springs 53 may be put under different degrees of compression according to the portion of the sole to which they apply pressure. For example, the supplementary roll next but one to the form 110 carrier may be under a heavier spring pressure than are the adjacent rolls on either side so that when the parts are in the position illustrated in Fig. 4, a heavier pressure 115 will be applied to the shank than to either 120 toe or heel.

As shown in Fig. 4, the shape of the yielding engaging pieces 22 and the sections 21 of the form are such that when the form is in operative position upon the shoe, what is 125 then the upper surface of the sections constitutes a substantially continuous, curved surface closely approximating the form of an arc, the center of curvature of which is the axis of the sector levers 6, so that the 130

supplementary pressure rolls 51 will roll over this surface, each roll in turn applying pressure to each portion over which it passes. It is obvious, however, that a greater or less pressure can be applied not only by the form carrier but by the supplementary rolls as well, to any particular or desired portion of the form by increasing or diminishing the thickness of the section overlying the portion of the sole in question. Preferably the sections over the shank portions of the sole will be slightly thicker than those over other parts, in order to increase the pressure upon the shank.

As already pointed out, the pressure spring 46 of the form carrier is a relatively heavy spring, while those which hold the supplementary rolls in engagement with the sections of the form are relatively lighter, the object of this arrangement for varying the pressure being to insure the proper laying or leveling of the sole by enabling each section of the form which operates upon a substantial portion of the surface of the sole to be applied to that portion under a pressure per unit of area, which, if necessary, may be so heavy that if applied simultaneously to the entire surface of the shoe sole would be liable to break or seriously damage the wooden last upon which the shoe was supported. While the spring pressure of the supplementary rolls may be very substantially less than that of the form carrier, still they are sufficient to exert a very material pressure upon the form, which will also assist in the laying and leveling operation.

As shown, the sections of the form are of such a length in the direction of the longitudinal axis of the shoe, and the supplementary rolls are of such a number and spaced such a distance apart that not only will the various sections of the form, after they have been applied to the sole by the form carrier, be maintained under at least a substantial minimum pressure, but the pressure will vary being increased from, and then reduced to, this minimum from time to time, as the form carrier and rolls pass over the sections of the form. At no time, however, will the total pressure exerted through the form upon the wooden last be sufficient to fracture or injure the same.

In the specific embodiment of the invention illustrated in the drawings, the form is applied first to the heel and then progressively along the sole to the toe, and when the form is removed the reverse operation takes place, first the toe portion, then the ball, and finally the shank and heel portions being removed. Such an arrangement and operation, it will be observed, enables pressure to be applied to the shank portion, which ordinarily is the part of the shoe sole most difficult to lay and level, for a longer period of time than to the ball and toe por-

tions, since it is applied to the shank portion of the sole sooner and removed from it later than at the ball and toe portions. Moreover, the shank portion is subjected to a greater number of pressures than are the ball and toe portions, since the shank sections of the form are acted upon by the second supplementary roll in the series, as well as by the form carrier and the first roll, the ball and toe portions at the most having pressure applied through the form carrier and only the first of the supplementary rolls. If desired, however, pressure may be applied progressively over the sole from any other extremity or margin thereof or even from some point within such margin.

In order that the form shall be brought in proper position upon the shoe sole with the various portions or sections of the form exactly upon that part of the shoe sole on which they are designed to operate, the block 32, carrying the vertical post 31 which anchors one end of the form, is adjustably mounted upon the horizontal guideway 58 (see Figs. 8 and 9) of the jack, being adjusted by hand along the same and secured in its adjusted position by the set screws 59. The heel and toe supports 2 and 3 are also adjustably mounted upon the guideway 58 to permit their being moved nearer to or farther from each other according to the size or length of the shoe they are to support, and this adjustment is effected by means of the threaded shaft or spindle 61 mounted in a bearing in the upturned end 62 of the guideway and held from longitudinal movement by the collar 63 on the back side of the bearing and the hub of the adjusting hand wheel 64 on the front side. The front and the rear portions of this shaft are oppositely threaded, one portion being provided with a right-hand thread, and the other with a left-hand thread, each portion passing through correspondingly threaded holes in the depending bosses or lugs 65 and 66 on the bottoms of the heel and toe supports respectively. A rotation of the adjusting hand wheel 64 in one direction moves the heel and toe supports toward each other, while if the hand wheel be turned in the opposite direction, the supports will be moved apart. It is desired, however, to position the shoe by its shank portion, and since this is nearer the heel support than the toe support, the threads upon the spindle are given a different pitch or number per inch, those on the rear portion being of less pitch or of greater number per inch than on the front portion, so that when the hand wheel 64 is rotated the heel support will be moved along the guideway toward or from the toe support at a less rate than the toe support is moved along the guideway toward or from the heel support, the pitch of the threads on the rear portion being just enough less than of those

on the front portion to keep the shank of the shoe substantially always in the same absolute position, no matter whether the shoe be long or short. The jack is also provided with means whereby the heel and toe supports may be adjusted vertically to accommodate different shapes and sizes of lasts. As shown in Fig. 9, the bottom piece 71 which, as shown in Fig. 3, is fixedly secured to the frame of the machine by the screws 72, is provided with the guideway 73 in which is mounted to slide the adjusting piece 74 having the inclined slots 75 in its front and rear portions. A threaded adjusting spindle 76 mounted in bearings in the front wall 77 of the bottom piece 71 is provided with a squared nut 78 to receive a wrench or handle whereby the spindle may be turned to adjust the piece 74 forward or backward in its guideway in the bottom piece 71. Secured to each side of the piece 71 by the screws 81 are the side pieces 82 having the vertical slots 83 (see Figs. 4 and 9). These slots receive in their upper portions the studs 84 which are screwed into the V-shaped bosses 85 extending downward from each side of the guide piece 58. In the lower portion of the vertical slots 83 are the ends or heads 86 of the studs 87. Secured in the bottoms of these V-shaped projections 85 are the middle portion of these studs which pass through the inclined slots 75 in the adjusting piece 74. If it be desired to raise the toe and heel supports, it is only necessary by means of a wrench or other suitable device to rotate the adjusting spindle 76 in such a direction as to force the adjusting piece 74 rearwardly which will cause the inclined slots 75 to force the studs 87 upwardly in the vertical slots 83, thus raising the guide piece 58 and all the parts, including the toe and heel supports carried thereby. Rotation of the spindle in the opposite direction lowers these parts.

The actuating mechanism for each sector lever 6 consists of a crank upon a shaft connected with the arm 8 of the sector lever, a power shaft, suitable speed reducing devices between the power and the crank shaft, and mechanism for controlling the rotation of the power shaft. In order that the sole may be properly laid or leveled, it is desirable that the actuating mechanism for the form be so designed that it may repeat its cycle of operation one or more times at the will of the operator, and preferably that after such mechanism has been once set in operation, it will continue to operate until thrown out of operation by the attendant. It is also desirable on this class of machines that the mechanism should automatically come to rest in the most convenient position for the operator to remove the old work and insert the new. Furthermore, in a twin or double machine, such as is illustrated in the draw-

ings, it is of advantage to so construct and arrange the controlling mechanism that, normally, when one set of mechanisms is set into operation, the other set will cease operation, provision being made, however, for stopping both sets when desired.

In United States Letters Patent No. 861,746, granted July 30, 1907, is shown actuating and controlling mechanism which I had invented and embodied in a sole pressing machine of the rolling pressure type. Inasmuch as substantially the same mechanism is employed in the sole pressing machine which forms the subject of the present invention, any detailed description of the same is unnecessary, the construction and mode of operation of such mechanism being fully set forth in the above-mentioned patent. Briefly described, the actuating mechanism for the sector levers consists of two crank shafts 91, disconnected from one another but with coincident axes. Each crank 92 is connected by means of the link 93 with the end of the actuating arm 8 of the sector lever 6. Secured upon the end of each shaft and outside the frame of the machine is the large gear 94 which engages the worm 95 upon the power shaft 96. Loosely mounted upon the rear end of the shaft is the driving pulley 97 which forms one member of a cone clutch, the other member being rigidly secured upon the shaft. A movement of the driving pulley to the right in Fig. 1 causes the clutch members to engage, and starts the worm and gear in operation, while a movement in the opposite direction disconnects the clutch and stops the form carrier actuating mechanism. Two treadles 101 are provided, conveniently located for the operator at the front of the machine, which, through a train of mechanism which need not here be described, actuates the shifting lever 102 to cause the clutch to release or engage and the brake shoe 103 to be thrown into or out of contact with the brake disk 104 on the power shaft. The cam 105 on the end of the crank shaft operates, as fully set forth in the patent referred to, through the lever 106, to cause the actuating mechanism to be automatically thrown out of operation only when the sector lever has reached its backward position, as shown in full outline in Fig. 1. The driving belt is led from an overhead countershaft around and beneath the loose pulleys 97, passing up over the idler 107 on its way from one of said pulleys to the other.

The modes of operation of the specific mechanisms of the illustrated machine have already been set forth in connection with the description thereof. The general mode of operation of the machine as a whole is as follows: The jack having been adjusted for the sizes of shoes to be operated upon and a form of the proper size and shape

having been secured upon the form-carrier, the last with the shoe upon it is placed in position upon the jack and the machine set in operation by pressing down the proper treadle. As the sector lever swings forwardly, the form is applied one portion at a time to the sole of the shoe, beginning at the heel, and under the heavy pressure of the form-carrier springs, and as the carrier advances over the sole one after another of the supplementary pressure rolls are brought into contact with the upper surface of the form and impart a rolling pressure to the sole. After the crank passes its center the sector lever moves rearwardly, carrying the supplementary rolls along the form and finally out of contact therewith, while the form-carrier removes the form one portion at a time from the sole. In the meantime the operator is adjusting another last with its shoe upon the other jack of the machine and as soon as this is accomplished depresses the other treadle to start the other set of mechanism in operation, at the same time bringing the first set to rest so that the shoe and last may be removed and another shoe on its last inserted in the machine. If it be desired to stop one set of mechanism without starting the other in operation this may be accomplished by partially depressing the starting treadle as set forth in said United States patent No. 861,746.

In the preceding specification and in the accompanying drawings what is now considered the preferred form of the present invention has been described and illustrated. It is to be understood, however, that the present invention may be embodied in many other and different forms of mechanism without departing from the spirit thereof. Furthermore, many of the features of the above described invention need not necessarily be employed in combination with each other and with the other mechanisms herein shown and described, but are capable of use apart therefrom and in other and different combinations.

Having thus described the present invention and explained the principle thereof and what is now considered the best mode of applying that principle, what is claimed is:

1. A sole pressing machine having, in combination, a sole pressing form, a shoe supporting jack, and means for relatively actuating the form and jack to apply the form progressively to the sole until the form is in contact with the entire surface of the sole and to apply pressure to the portion of the sole to which the form is first applied and a heavier pressure to a portion of the sole to which the form is later applied, substantially as described.

2. A sole pressing machine having, in combination, a sole pressing form, a shoe supporting jack, and mechanism for relatively

tively actuating the form and jack to apply the form first to the heel portion of the sole and then progressively along the same until the form is in contact with the entire surface of the sole and to apply a heavier pressure to the shank portion of the sole than to the heel portion, substantially as described. 70

3. A sole pressing machine having, in combination, a sole pressing form, a shoe supporting jack, and means for relatively actuating the form and jack to apply the form progressively from the heel to the toe until the form is in contact with the entire surface of the sole, substantially as described. 75

4. A sole pressing machine, having, in combination, a shoe supporting jack, a sole pressing device adapted to engage the surface of the shoe sole, a pressure applying device, and means for moving the pressure applying device progressively over the sole pressing device to apply pressure through the sole pressing device to the sole progressively in the direction of movement of the pressure applying device, substantially as 80 described. 85

5. A sole pressing machine, having, in combination, a sole pressing form, a shoe supporting jack, and automatically acting mechanism for relatively actuating the form and jack to apply pressure to a predetermined portion of the sole, then to partially relieve the pressure upon said portion, and then to increase the pressure thereon, substantially as described. 95

6. A sole pressing machine having, in combination, a sole pressing form, a shoe supporting jack, and automatically acting mechanism for relatively actuating the form and jack to apply a heavy and subsequently 105 a relatively lighter pressure to the same substantial portion of the shoe sole, substantially as described.

7. A sole pressing machine, having, in combination, a sole pressing form, a shoe supporting jack, and automatically acting mechanism for relatively actuating the form and jack to apply a heavy pressure upon first one portion of the sole and then upon another portion, and to maintain a relatively lighter pressure upon the portion of the sole not under said heavy pressure while applying said pressure to the other portion of the sole, substantially as described. 110

8. A sole pressing machine, having, in 120 combination, a sole pressing form, a shoe supporting jack, and mechanism for relatively actuating the form and jack to apply a heavy pressure progressively along the shoe sole and to maintain a relatively lighter 125 pressure upon one portion of the sole while applying said heavy pressure to another portion of the sole, substantially as described.

9. A sole pressing machine having, in 130

- combination, a flexible sole pressing form adapted to be in contact with different portions of the shoe sole at the same time, a shoe supporting jack, and automatically acting mechanism for relatively actuating the form and jack to maintain pressure for different periods of time upon different portions of the shoe sole, substantially as described.
10. A sole pressing machine having, in combination, a sole pressing form adapted to be in contact with the shank and with other portions of the shoe sole at the same time, a shoe supporting jack, and mechanism for relatively actuating the form and jack to maintain pressure for a longer period upon the shank than upon other portions of the sole, substantially as described.
11. A sole pressing machine having, in combination, a sole pressing form adapted to be in contact with different portions of the shoe sole at the same time, a shoe supporting jack, and mechanism for relatively actuating the form and jack to apply pressure a different number of times to different portions of the shoe sole, substantially as described.
12. A sole pressing machine having, in combination, a sole pressing form adapted to be in contact with the shank and other portions of the sole at the same time, a shoe supporting jack, and mechanism for relatively actuating the form and jack to apply pressure for a greater number of times to the shank than to other portions of the sole, substantially as described.
13. A sole pressing machine having, in combination, a sole pressing form, a shoe supporting jack, and mechanism for relatively actuating the form and jack to apply the form to the sole and to apply pressure progressively to the form from one end to the other, substantially as described.
14. A sole pressing machine, having, in combination, a shoe supporting jack, a flexible sole pressing device unsupported intermediate its ends when in engagement with the shoe sole, connections at each end of the device for supporting the device, means for producing a relative bodily movement of the jack and sole pressing device to bring the device into engagement with the shoe sole, and mechanism operating independently of such bodily movement for applying pressure to the device intermediate its ends, substantially as described.
15. A sole pressing machine having, in combination, a sole pressing form unsupported intermediate its ends when in normal operative position, connections at each end of the form for supporting the form, means for supporting the form intermediate its ends when in inoperative position, and mechanism for relatively actuating the form and jack, substantially as described.
16. A sole pressing machine having, in combination, a sole pressing form comprising a plurality of connected sections, a shoe supporting jack, and mechanism for relatively actuating the form and jack to apply the form one section at a time to the bottom of the shoe sole, substantially as described.
17. A sole pressing machine, having, in combination, a flexible sole pressing form, a shoe supporting jack, mechanism for relatively actuating the form and jack to cause the form to engage the shoe sole, and power actuated auxiliary mechanism for applying pressure to the form, substantially as described.
18. A sole pressing machine having, in combination, a sole pressing form, a shoe supporting jack, a yielding support for one end of the form, an independently mounted movable support for the other end of the form, and mechanism for actuating the movable support, substantially as described.
19. A sole pressing machine, having, in combination, a flexible sole pressing form, the several portions of which are shaped to correspond to the predetermined portion of the shoe sole they are to engage, an oscillatory form carrier, a shoe supporting jack, and mechanism for relatively actuating the form and jack to cause the carrier to apply the form, one portion at a time, to the predetermined portions of the shoe sole, substantially as described.
20. A sole pressing machine having, in combination, a flexible sole pressing form, an oscillatory form carrier to which one end of the form is attached, an anchor for the other end of the form, a shoe supporting jack, and mechanism for relatively actuating the form and jack to cause the carrier to apply the form one portion at a time to the shoe sole until the form is in contact with the entire surface of the shoe sole, substantially as described.
21. A sole pressing machine having, in combination, a sole pressing form comprising sections pivoted to one another, a shoe supporting jack, and mechanism for relatively actuating the form and jack to apply the form one section at a time progressively along the sole until the form is in contact with the entire surface of the sole and then to remove the form one section at a time progressively along the sole in the opposite direction, substantially as described.
22. A sole pressing machine having, in combination, a sole pressing form, a shoe supporting jack, and mechanism for relatively actuating the form and jack to apply the form to the shoe sole and to apply a rolling pressure to the form, substantially as described.
23. A sole pressing machine, having, in combination, a sole pressing form, a shoe supporting jack, and mechanism for relatively actuating the form and jack to apply

the form to the shoe sole and to apply a rolling pressure to the form progressively from the heel to the toe, substantially as described.

24. A sole pressing machine, having, in combination, a sole pressing form, a shoe supporting jack, mechanism for relatively actuating the form and jack to apply a heavy pressure to a predetermined portion of the sole, and auxiliary mechanism for relatively actuating the form and jack to apply a lighter pressure to the same portion of the sole, substantially as described.

25. A sole pressing machine having, in combination, a sole pressing form comprising a plurality of sections, the sole engaging surfaces of which correspond to the contour desired for the shoe sole, and the reverse surfaces of the sections constituting, when the form is applied to a shoe sole, a substantially continuous surface, a shoe supporting jack, and mechanism for relatively actuating the form and jack to apply the form to the shoe sole, and a roll for engaging the reverse surfaces of the sections of the form to apply pressure to the sole, substantially as described.

26. A sole pressing machine having, in combination, a flexible sole pressing form, the sole engaging surfaces of which correspond to the contour desired for the shoe sole, and the reverse surfaces of the sections constituting, when the form is applied to the shoe sole, a substantially continuous surface higher at the shank than at other portions of the sole, a shoe supporting jack, and mechanism for relatively actuating the form and jack to apply the form to the shoe sole, and a roll for engaging the reverse surfaces of the sections of the form to apply a greater pressure to the shank than to other portions of the sole, substantially as described.

27. A sole pressing machine having, in combination, a flexible sole pressing form, an oscillatory form carrier to which one end of the form is attached, an anchor for the other end of the form, mechanism for relatively actuating the carrier and jack to cause the carrier to apply the form to the shoe sole, and means for oscillating the carrier to cause it to remove the form from the shoe sole, substantially as described.

28. A sole pressing machine having, in combination, a flexible sole pressing form, an oscillatory form carrier to which one end of the form is attached, an anchor for the other end of the form, a shoe supporting jack, oscillating arms supporting the carrier, and means for actuating said arms to move the carrier first in one direction and then in the other, substantially as described.

29. A sole pressing machine having, in combination, a flexible sole pressing form, an oscillatory form carrier, means for supporting the carrier, a pressure roll carried by said means, and mechanism for oscillating

said means to cause the carrier to apply the form to the sole and the roll to apply pressure to the form, substantially as described.

30. A sole pressing machine having, in combination, a flexible sole pressing form, an oscillatory form carrier, a shoe supporting jack, means for moving the carrier over the jack to apply the form to, and to remove it from, the shoe sole, and means independent of the form for rotating the form carrier in its form-removing movement, substantially as described.

31. A sole pressing machine having, in combination, a flexible sole pressing form, a spring pressed oscillatory form carrier to which one end of the form is attached, an anchor for the other end of the form, oscillating arms for supporting the carrier, spring pressed pressure rolls carried by the arms, and means for oscillating the arms to cause the carrier to apply the form under pressure to the shoe sole and the pressure rolls to apply pressure to the form, substantially as described.

32. A sole pressing machine having, in combination, a sole pressing form, a shoe supporting jack, means for relatively actuating the form and jack to apply the form to the shoe sole, and a plurality of pressure rolls for applying pressure to the form, substantially as described.

33. A sole pressing machine having, in combination, a sole pressing form, a shoe supporting jack, means for relatively actuating the form and jack to apply the form to the shoe sole, and a plurality of pressure rolls for applying pressure to the form, said rolls having independent spring-pressed supports, substantially as described.

34. A sole pressing machine having, in combination, a flexible sole pressing form, a shoe supporting jack, an oscillatory form carrier to which one end of the form is attached, an anchor for the other end of the form, means for relatively actuating the jack and carrier to apply the form to the shoe sole, and means for relatively adjusting the jack and the anchor to position the form on the sole, substantially as described.

35. A sole pressing machine having, in combination, a sole pressing form, a shoe supporting jack having toe and heel supports adjustable toward and from each other, a spindle having right and left hand threads of greater and lesser pitch for actuating the toe and heel supports respectively, means for actuating the spindle, a fixed support on the jack for the heel end of the form, and mechanism for relatively actuating the form and jack, substantially as described.

36. A sole pressing machine having, in combination, a flexible sole pressing form, a shoe supporting jack, a support on said jack to which one end of the form is piv-

totally connected, and mechanism for relatively actuating the form and jack, substantially as described.

37. A sole pressing machine having, in combination, a sole pressing form, a shoe supporting jack, a support for one end of the form, means for simultaneously adjusting the jack and said support at right angles to the plane of the surface of the sole, and mechanism for relatively actuating the form and jack, substantially as described.

38. A sole pressing machine, having, in combination, a shoe supporting jack, a sole pressing form comprising a plurality of pivotally connected sections each section provided with a sole engaging face on one side and a pressure receiving face on the other side independent of the pivotal connections, means for relatively actuating the jack and form to apply the form to the sole of a shoe on the jack, and means for applying pressure to the pressure receiving face of the form, substantially as described.

39. A sole pressing machine, having, in combination, a shoe supporting jack, a sole pressing form comprising a plurality of pivotally connected sections each section provided with a sole engaging face on one side and a pressure receiving face on the other side, the pressure receiving faces being shaped to make, when the form is applied to a shoe sole, a substantially continuous pressure receiving surface, means for relatively actuating the jack and form to apply the form to the sole of a shoe on the jack, and means for applying pressure to the pressure receiving surface of the form, substantially as described.

40. A sole pressing machine, having, in combination, a shoe supporting jack, a sole pressing form comprising a plurality of pivotally connected sections having a broken line of jointure between adjacent sections, and means for relatively actuating the jack and form to apply the form to the sole of a shoe on the jack, substantially as described.

41. A sole pressing machine, having, in combination, a shoe supporting jack, a sole pressing form comprising a plurality of pivotally connected sections the adjacent faces of each pair of sections being provided one with a recess and the other with a projection entering said recess to break the line of jointure, and means for relatively actuating the jack and form to apply the form to the sole of a shoe on the jack, substantially as described.

42. A sole pressing machine, having, in combination, a shoe supporting jack, a sole pressing device adapted to engage the surface of a shoe sole, and a pressure roll for applying pressure to said device, substantially as described.

43. A sole pressing machine, having, in combination, a shoe supporting jack, a sole pressing device, means for applying said device to the surface of the sole, and means operating thereafter to apply pressure progressively over said device, substantially as described.

44. A sole pressing machine, having, in combination, a shoe supporting jack, a sole pressing device, and mechanism operating automatically, first to apply said device to the shoe sole, and then to apply rolling pressure to said device, substantially as described.

BENJAMIN F. MAYO.
